By Cleopha Floyd
H. T. T. Y.

UNITED STATES PATENT OFFICE

JOHN E. DUNGAN, OF CHICAGO, ILLINOIS, ASSIGNOR, BY MESNE ASSIGNMENTS, OF ONE-HALF TO REMINGTON RAND INC., OF BUFFALO, NEW YORK, A CORPORATION OF DELAWARE

FOLDING CREDIT REGISTER

Application filed July 14, 1925, Serial No. 43,531. Renewed January 9, 1932.

The present invention has to do with a sectional credit register in which a large number of accounts may be kept in a relatively small structure, and which is adapted to be folded to conserve space.

Among the objects of the invention are the following:

An improved type of credit register having sections adapted to fold one upon another for compactness; an unique arrangement of two or more series of drawers whereby they may be folded into unit parallel sections, the arrangement providing additional useful storage space; improved fireproofing means and protection in a credit register, or in a device comprising a plurality of drawers adapted to hold sales tickets; improved means for holding the drawers in one of the sections of a device of the character described, against displacement during the opening, closing and transporting operations of said section; and an unique member for locking the drawers in a credit register against accidental displacement.

These, and such other objects as may hereinafter appear, are attained by the novel construction, combination, and arrangement of the several elements which constitute the invention, one embodiment of which is illustrated in the accompanying drawings, hereby made a part of this application, and in which:

Figure 1 is an end view, partly in elevation, and partly in section, of a register embodying the invention.

Figure 2 is a top view of the lower section of the register illustrated in Figure 1;

Figure 3 is a front elevation of the upper section of such register, a drawer holding member being in position; and

Figure 4 is a horizontal section on the line 4-4 of the Figure 3 looking in the direction of the arrows.

Like reference characters are used to designate similar parts in the drawing and in the description hereinafter given of the embodiment of the invention.

By reference to Figure 1, which shows a register of the type hereinafter described in open position, it will be noted that the regis-

ter comprises two sections having a plurality of drawers adapted to hold credit or sales slips, hingedly connected, one to another. One of said sections is adapted to be folded down over the other section thereof. Accessibility to all of the drawers contained in both sections is made perfectly apparent from an examination of Figure 1.

The bottom section of the device is generally rectangular in configuration, and is ordinarily manufactured of folded metal sheets. Said bottom section designated A, comprises a bottom 10, an end member 11, an opposite end member 12, and side members 13. These members may be produced by conventional folding means or other manufacturing expedients common to the metal art.

Ordinarily the material of the end 11 and 12, and sides 13 is extended inwardly to form a part of the front of section A, which front more properly is designated the top thereof.

As will be noted in Figure 2, the material of such front is folded to provide a narrow edge flange or flat section 14 on three sides thereof, a contiguous V-shaped trough section 15 extending about said three edges thereof, and a broader flange at the end of section A which connects the upper section, designated B; the trough 15 being arranged at this end adjacent said broader flange.

A second narrow flat flange 16 is arranged adjacent the V-shaped trough section 15 on all sides.

From an examination of the wall 17 and 18, which limits the storage space contained in section A and to which access may be had through the top thereof, it will be noted that such storage space is arranged at an angle, or in other words, is obliquely disposed. A second wall 19 is arranged in proximity to wall 17, in order to provide a relatively narrow open storage section divided by partitions 20, generally equidistantly spaced. A plurality of pigeon holes may thus be provided.

Between the transverse walls 18 and 19, a number of dividers 21 are provided to define adjacent compartments. These are of the

same general type as are illustrated in the co-pending joint application of the applicant here, John E. Dungan, and one Richard James, filed May 10, 1924, and numbered 5 712,439 which application has matured into Patent No. 1,745,218, dated January 28, 1930.

Each of the dividers 21 has as a part thereof a plurality of shelves 22. Internal end or side members 23, adjacent sides 13 have 10 shelves 24 parallel to shelves 22. Between the sections 21, and said sections and members 23, upon the shelves 22 and 24, a plurality of drawers 25 having pin stops 26, similar to those described in said co-pending 15 application, are arranged. Said drawers 25 are adapted to be removed by a pull upon a handle 27 formed integrally therewith, and are lifted upwardly in an oblique direction. When sufficiently removed, they are allowed 20 to become horizontal, taking the direction of the open top of section A.

In this manner, complete access to said 25 drawers 25 is obtained, for the pin 26 acting in the space in the ends 23 and separators 21 provided by cutting the material thereof to form the shelves 22 and 24, and folding these shelves over, permits sufficient removal of the drawer 25 from section A to give access 30 to its entire contents.

35 At one end of section A is a drawer C having a handle portion 28. Said drawer C comprises sheet metal portions including a bottom 29 and sides 30 and is open at its top. It is completely encased in a section 35 of sheet material designated 31 and having a flanged portion 32 adapted to be secured to the material of sides 13.

Section B is hingedly connected to section 40 A by a piano hinge member or other suitable hinge 33. Section B comprises a back 34 and an end 35 slightly oblique and to which the hinge 33 is secured. Said section 35 is adapted to rest upon the portion of section A enclosing drawer C. An end 36 at a 90° angle to back 34, and sides 37 also at 90° thereto, complete the walls of section B.

45 At the open front of section B are four flanged sections 38, which are equidistantly removed from the sides 37 and the ends 35 and 36, and which include an inverted V-shaped section 39 which is adapted to be inserted into and fit snugly in the trough of section A when section B is folded there-over.

50 Spaced from the ends 35 and 36 and the side 37 is a second wall 40, see Figure 4. This wall provides an air space sufficient for fire protection for insulating material between the contiguous external walls and the internal wall 40. Adjacent to the wall 40 contiguous to the sides 37, is a shelf-supporting member 41 each member 41 having a plurality of evenly separated shelves 42. Between members 41 are a plurality of separators 43. A sheet of metal folded upon itself is used

to provide separators 43 with a double wall, a closed front and an open back, and in the walls of said separator 43, a number of shelves 44 are provided by cutting the material thereof and folding such material at an angle of 70 90°.

Upon the shelves 42 and 44, a number of drawers 45 are arranged. Each of said drawers is held within the section B by a pin 46, and is adapted to be actuated by a handle 47 generally integral therewith. The construction of the end members 41, the separators 43, the drawers 45, and the pins 46 in said drawers is the same as in the previously referred to joint application for patent. 80

It is quite manifest that if an effort is made to close section B upon section A without the drawers 45 in section B being secured in place, many of said drawers will fall out and probably make it difficult or impossible to 85 close section B over section A. In order to obviate this difficulty, I have provided a drawer locking member D.

Said member D comprises a plurality of sheet metal strips 50 arranged vertically. 90 To the external members 50, an angle iron 51 adapted to engage one of the outer rows of drawers 45 is secured. For each internal member 50, a double angle iron 52 is provided. Said member 52 is adapted to engage 95 two series or rows of drawers 45 concurrently at opposite sides of a separator 43.

Two or more cross members 53 are adapted to hold the vertical members 50 in rigid alignment. Upon the bottom member 53, tongues 54 are arranged, and said tongues 54 are adapted to be inserted into upwardly opening apertures in the material of flange section 38. The tongues 54 are inwardly bent for this purpose. 100

At the top of the member D, one or more latch members 55 are provided. Such latch members 55 comprise a semi-circular portion of material, eccentrically mounted upon a shaft 56. Said shaft 56 has an operating handle 57 and is pivotally secured in members 53. Members 55 are bent as indicated in Figure 1, so that when turned to a position opposite that shown in Figures 1 and 3, said members are entirely disengaged from the upper flange 38, which flange is provided with downwardly opening slots or apertures for the purpose of receiving said locking member 55. 110

It is quite manifest that in order to place the member D in position, the tongues 54 thereof are first inserted into the apertures provided for their reception, and the latch members must be turned to a position diametrically opposed to that shown in Figure 125 3. Member D is pressed in upon the drawers 45, and while so held, the handles 57 are turned until the material of the latch members 55 is inserted into the apertures in the flange 38 provided therefor. Removal is ac- 130

complished by reversing the latching operation and lifting the tongues 54 out of position.

When the member D is in position, section 5 B may be folded over section A. In order to render the device proof against burglary, or inquisitors when folded, a lock 60 on the end thereof is provided. A handle 61 facilitates separation of the two parts, A and B.

10 When closed, the device is indeed compact and is adapted to be used in a relatively small space. It may be conveniently moved about. When open it occupies a relatively small amount of desk space and is adapted 15 for use in limited quarters. In the trough flange 15, it is usual and customary to seat a strip of asbestos 70. When the flange 39 is pressed into trough 15, it impinges the asbestos 70, rendering the closed cabinet air 20 tight and greatly increasing fire resistance.

It will be noted that the two sections A and B fasten one against the other when closed and that the interfitting parts comprise as to one section, a continuous groove, 25 and as to the other section, a continuous strip fitting into said groove. This construction has a great advantage in fire protection for there are no openings or breaks in the seam between the parts. No flame or hot gases 30 therefore can penetrate into either section through the interfitting parts.

I claim:

1. A credit register having normally superposed sections, walls in each section, a 35 plurality of shelves on each wall, the walls having slots above each shelf and parallel thereto, a plurality of drawers on said shelves, each of said drawers having side walls and a pin traversing the drawer and 40 projecting through said side walls into opposed slots, said drawers being of less length than said slots and said pins being at the rear of said drawers and of appreciably less diameter than the width of said slots where- 45 by said drawers may be drawn from out of contact with said shelves but maintained in proper position between opposed walls, and a hinged connection between said sections for effecting the disposition thereof in an- 50 gularly related planes, thereby rendering the drawers in each section independently removable in different planes.

2. A credit register having normally superposed sections, walls at the side of said 55 sections, a plurality of shelves on each wall, there being parallel slots in each wall above said shelves and extending to adjacent the front edge of the former, a drawer on each pair of shelves and having side walls, each 60 drawer having a transversely arranged pin in said side walls near the rear thereof and being of less length than said slots, the width of said slots being several times the diameter of said pin, a hinge connecting member 65 between said sections for effecting the dis-

position thereof in angularly related planes, thereby rendering the drawers in each section independently removable in different planes, and a detachable member, U-shaped in cross section, having an end pivotally associated with one of said sections and extending over the front of said wall and projecting inwardly to the front of said drawers to lock the drawers in said sections prior to arranging said sections in their normally superposed relation.

JOHN E. DUNGAN.
